UNITED STATES PATENT OFFICE

158,770

MOCCASIN

Wallace C. Lawrence and Hubert L. Horsman,
Bandera, Tex., assignors to Mustang Moccasin
Company, Bandera, Tex., a corporation

Application March 6, 1950, Serial No. 8,359

Term of patent 14 years

(Cl. D7—7)

To all whom it may concern:

Be it known that we, Wallace C. Lawrence and Hubert L. Horsman, citizens of the United States, residing, respectively, at the town of Bandera, in Bandera county, State of Texas, have invented a new, original, and ornamental Design for a Moccasin, of which the following is a specification, reference being had to the accompanying drawing, forming a part thereof.

Fig. 1 is a top view of a moccasin, showing our new design.

Fig. 2 is a side view of the same.

We claim:

The ornamental design for a moccasin, as shown.

WALLACE C. LAWRENCE.
HUBERT L. HORSMAN.
